ELECTRIC DISCHARGE SYSTEM

Carl J. R. H. von Wedel, West Orange, N. J., assignor to Thomas A. Edison, Incorporated, West Orange, N. J., a corporation of New Jersey

Application July 31, 1935, Serial No. 33,967
Renewed January 18, 1939

12 Claims.

(Cl. 176—1)

This invention relates to electric discharge systems, and more particularly to systems where-in the discharge takes place in a gaseous atmosphere. Throughout the specification the term "gaseous" has been employed as an adjective to denote either a gas or a vapor or a combination of gases and/or vapors, while the terms "gas" and "vapor" have each been used in a more specific sense. While not in all aspects limited thereto, the invention has special reference to discharge systems and devices for operation on alternating current.

An important objects of the invention is the provision of a gaseous discharge device or lamp for emitting ultra-violet radiations, particularly those of the so-called "Dorno" spectrum of wavelengths between 2900 and 3100 Angstrom units, capable of being inserted in an ordinary commercial power supply socket and of being operated at will in simple manner by the layman.

A more general object is the provision of an improved self-contained gaseous discharge device arranged for starting and operating when connected directly with a commercial supply socket without auxiliary apparatus.

Another object is the provision of a discharge system employing novel and useful mechanical and electrical arrangements of ballasting means.

Another object is the provision of an improved mutual circuit arrangement of ballasting means and cathode heating means.

Another object is the provision of a simplified circuit arrangement for the cathode heating means.

Another object is the provision of simple and improved means for automatically starting the discharge.

Another object is the provision of simplified mutual circuit arrangements of the discharge starting means and other portions of the system.

Still another object is the provision of an improved anode and mutual arrangement of anodes for a gaseous discharge device.

Still another object is the provision of ballasting means capable of disposition and operation within the gaseous atmosphere of a discharge device and adjacent its discharge column, and of methods of preparing the same.

Still another object is the provision of simple means for controlling the potential gradient of a metal vapor discharge device.

Other and allied objects will more fully appear from the following description and the appended claims.

55 In the detailed description of my invention

hereinafter set forth reference is had to the accompanying drawings, of which:

Figure 1 is a view in vertical cross-section of one form of discharge system according to my invention;

Figure 2 is an enlarged view of the electrode 5 of Figure 1 in more complete section;

Figure 3 is a perspective view of one of the anodes of the device of Figure 1, in inverted position;

Figures 4 and 5 are horizontal cross-sectional views respectively taken along lines 4—4 and 5—5 of Figure 1;

Figure 6 is a view generally similar to Figure 1, but illustrating a second form of discharge system according to my invention;

Figure 7 is a horizontal cross-sectional view taken along the line 7—7 of Figure 6;

Figure 8 is a view generally similar to Figures 1 and 6 but illustrating a third form of discharge system according to my invention; and

Figure 9 is a simplified schematic view of the system of Figure 8.

Reference is first directed to Figure 1. Herein appears the elongated glass envelope 1, which for purposes of light emission in the ultra-violet and particularly the Dorno spectrum may be of "Uviol" or "Corex D" or equivalent glass. At the respective extremities of the envelope two stems, 2 and 3, are sealed to form an air-tight enclosure; this is evacuated of air and contains a filling of rare gas or a rare gas mixture, for example argon and/or krypton, at a pressure of a few mm. Hg, and a source 4 of metal vapor—for example a globule of mercury—shown clinging to the walls in the lower section of the tube. The stem 3 carries the electrode 5 including the cathode 6, all as hereinafter described. The stem 2 carries two lead-in wires 20 and 21, respectively connected with the two contact elements of the Edison screw base 37 secured to the outside of the envelope extremity adjacent stem 2; these wires as they pass inwardly from the stem are shielded in any suitable manner, as by glass tubings 24, which may for example be integral with the stem 2. On and in electrical contact with the respective lead-in wires are mounted the anodes 25 and 26, so that they are electrically at the extreme potentials impressed across the device through the base 37.

In different figures herein I have illustrated anodes of different material and of different structure and mutual arrangement; the preferred anode, however, I have illustrated in Figure 1 (and in the detail Figure 3 and sectional

Figure 4). Each is formed of a sheet of refractory metal bent to provide the active anodic surface 25' and the flange surface 25'' at an acute angle (for example 60 degrees) to each other. A 5 suitably bent wire 23 may be welded, within the acute angle, to the rear face of the flange surface 25'' and to the outer extremity of the rear face of the active surface 25' (this outer extremity being conveniently slightly angled with 10 respect to the main surface 25'), and the wire 23 may be welded onto the respective lead-in wire 20 or 21. This support of the anodes is so carried out that the flange surfaces 25'' and 26'' of the two respective anodes are parallel with each other 15 and spaced apart a distance of the order of the electronic mean free path in the gaseous atmosphere within the device, and that the active surfaces 25' and 26' each face some 30 degrees outwardly from a line to the electrode 5 axial of the envelope and are very thoroughly shielded from 20 each other by the flange surfaces. The effect of this arrangement and of its individual features is so to shield the fields of the anodes as to reduce the danger of substantial ionic cross currents, 25 which lead to rapid disintegration and undesired heating of the anodes and cross-arching therebetween; to increase the length of possible anode-to-anode discharge paths, reducing danger of cross-arching; and, by the flange surfaces and generally large ratio of surface to volume, to increase 30 the cooling and decrease the operating temperature of the anodes, further reducing danger of cross-arching.

While carbon anodes, of other structure, may 35 be used and have been illustrated in later figures, I prefer the metallic anodes—particularly those having metallic surfaces sufficiently refractory to withstand the operating temperatures and characterized by oxyacids not more electro-negative than that of molybdenum. This is because 40 these materials disintegrating from these surfaces, and transported toward and succeeding in landing on the cathode element surface, do not significantly impair the operation of the cathode element or of the device as a whole—while in the 45 case of carbon anodes, disintegrating material reaching the cathode element surface reduces the effective area of that surface and causes carbon monoxide gas to contaminate the atmosphere within the device, and this causes an increase of potential gradient and unstable and undependable 50 operation of the device. Metals of the iron group and molybdenum, or alloys or platings thereof, have been found satisfactory for the anodes of Figure 1, depending on the supply voltage. To assist in reducing danger of cross-arching the 55 surface of the anodes is preferably arranged to have as high a cathode drop as possible; the cathode drop of the metallic surfaces may be increased to some extent by oxidizing the surface, provided the anode temperature in the de-gassing operation can be made substantially higher than the normal operating temperature but without decomposing the oxide. The dark 60 color of the oxidized surface also increases heat radiation and causes relatively cooler operation of the anodes. An oxidized molybdenum surface is satisfactory as it will not decompose or dissociate even with yellow-white temperatures. A 65 method of providing the high work function oxidized surface, alternative to oxidizing the anode metal itself, is to coat the same with a thin layer of a refractory metallic oxide compound.

On the stem 3 is mounted an electrode 5, comprising 70 a cathode element and heating means

therefor; the envelope 1 may conveniently be provided with a widened portion 1a about this electrode 5. The cathode element appears in Figure 1 as the generally helically formed heavy wire 6; this wire is preferably provided with a corrugated or pitted surface (provided for example by welding or plating therearound a relatively fine wire spiral) and is coated with an emissive oxide coating of the Wehnelt type. The upper extremity of the helically formed wire 6 is designated as 6'; the helix is preferably formed with a progressively reducing diameter in its lower portion, from which leads downwardly the lower wire extremity 6''. Reference may now be had for further details of the electrode 5 to the enlarged, partly sectional Figure 2, wherein the location of the cathode element 6—itself omitted for simplicity of illustration—is plainly indicated by the wire extremities 6' and 6''.

Co-axially surrounding the cathode element 6, 20 preferably in quite closely spaced relation thereto, is the cylinder 7 of refractory insulating material—such for example as Steatite, hereinafter more particularly referred to. On this cylinder 7 is wound a heater coil 8 of refractory metal 25 such as tungsten; this is provided with a center-tap 8c, dividing it into upper and lower halves 81, 82. Over the heater winding 8 is preferably coated (as by spraying) and dried a layer 8' of refractory insulating material, of such material 30 for example as that of which the cylinder 7 is formed. Against the ends of the cylinder 7 are fitted the circular nickel or other metal end members 13, as by means of bosses 13' extending slightly inwardly of the cylinder. These end 35 members are provided with central apertures 10, the cathode element extremity 6'' passing outwardly through this aperture in the lower end member 13 through an insulating bushing 11; in the upper end member 13 the aperture 10 serves 40 to admit the discharge to the cathode element 6. Co-axially surrounding the heater coil in spaced relation thereto is provided the cylindrical nickel or other metal shield can 9; this at its extremities is welded, to form a metallic enclosure for 45 the heater coil 8, to end members 13, which are therefore made of appropriate diameter and peripherally flanged. The cathode element extremity 6' is electrically connected to the shield can 9 by welding to the upper end member 13; and the heater center-tap 8c is also connected to the can 9, as by welding directly thereto. The heater extremities, 8a and 8b, are led outwardly of the heater enclosure through the respective end members 13 in small tubes 12, which may be of similar refractory insulating material to the cylinder 1, and are electrically connected with wires 14 and 15 which are anchored in stem 3. For further support of the electrode 5, and for de-gassing purposes as hereinafter mentioned, the cathode 60 element extremity 6'' may be welded to a lead-in wire 19 passing outwardly of the envelope through the stem 3, and the can 9 may be welded to the wire 16' and this in turn to the lead-in wire 16 likewise passing outwardly through the stem 3. 65

The electrode 5 then comprises a can, a cathode element therein and connected thereto, and a heater winding therein and centrally connected with the can. The extremities of the heater winding, represented by wires 14 and 15, are connected to the respective anodes through quite similar resistive ballasting and voltage dividing means, 28 and 29 respectively. In different embodiments of my invention these ballasting and voltage dividing means have taken different 70 75

forms and different physical dispositions; in all forms however it is desirable that they have a high positive resistance coefficient with respect to temperature, and accordingly a suitable material for the resistance element proper thereof is tungsten wire, because of its increase of resistance to some 10 times normal upon heating to temperatures of the order of 1400 degrees centigrade.

10 The ballasting means of Figure 1 are disposed within the envelope 1, and may be in the form of thin spirals 27 of the resistance wire imbedded in rods or tubings 27r (hereinafter referred to simply as rods) of refractory insulating material such as Steatite. While I intend thereby no limitation of my invention thereto, I may call particular attention to this material as one which I have found desirable for the refractory insulating media herein mentioned. This is a compound of aluminum oxide and/or alundum with a sintering material such as talc or calcium fluoride and the like. This and similar materials may be worked in a plastic state, and thereafter hardened and sintered, as by heating. 20 Windings to be imbedded in such materials may be wound upon a sintered rod or tubing thereof, and the coating in turn sintered. I prefer, however, to make the windings upon the rods with the latter in semi-plastic or hardened but un- 25 sintered form, thereupon to apply the coating of similar material over the winding and finally to heat or sinter the entire assembly as a unit. This serves to render quite homogeneous the material under, over and around the winding, reducing possible tendencies toward chipping off of the coatings. Another method of construction of such units as the resistive ballasting means of Figure 1, available for securing thorough homogeneity of the material, is the extrusion 30 of a rod of the material—the winding, already formed as a spiral, being coincidentally fed centrally out of the extruding aperture; and the extruded unit being thereafter sintered.

In Figure 1 the ballasting means 28 and 29 have each been divided into two portions, each portion comprising a rod 27r having wire 27 imbedded therein: 28 into the upper and lower portions 28a and 28b respectively, joined by the metallic sleeve 30; and 29 into the upper and lower portions 29a and 29b respectively, joined by the metallic sleeve 31. The ballasting means 28 has been provided with bottom and top caps 32 and 34 respectively, and the ballasting means 29 with the bottom and top caps 33 and 35 respectively. The bottom caps 32—33 and sleeves 30—31 hold the respective rod extremities firmly, while the top caps 34—35 are made of slightly larger internal diameter so that rods may expand or contract longitudinally by several millimeters without imparting strains to their supporting means. The sleeves and caps are subjected to heating by the rods 27r held thereby and also, at certain instants in certain periods of operation hereinafter mentioned, by electronic current entering them as anodes; as will hereinafter be apparent, however, their potentials relative to the potentials of other elements within the envelope 1 are such as to render them capable of undesired action as cathodes. Accordingly they must be of such material and surface as to obviate any emissivity at the temperatures they will attain; the surface should therefore be of good heat radiating properties and of high work function. Surfaced-oxidized molybdenum may be satisfactorily employed; I have,

however, obtained good results with metals of the iron group such as nickel by spraying the surface, to provide for less emissivity and better radiation, with a compound of the nature of Steatite and capable of sintering at the temperatures employed in degassing of the device. Similar material may be used to sinter the sleeves 30—31 and the caps 32—33 to the rods 27r—a convenient method of securing solid connections being to provide in the sleeve or cap slots (such as 30' in sleeve 30) and to spray the compound into the slots, and another method being to pre-groove the sleeve or cap and turn it onto the tubing. The extremities of the wires 27 in the two rods 27r terminating within sleeve 30 or 31 are jointly brought outwardly through the sleeve and welded to the outside, as at 31'; the extremity of the wire 27 in the rod terminating in any of the caps 32—33—34—35 is brought out through the end portion of the cap (which is originally in tubing form) and the end portion then pinched together to hold and connect with the wire. The caps 34 and 35 may be welded to the outer extremities of the respective anode surfaces 25' and 26', and the caps 32 and 33 to the top extremities of the respective wires 14 and 15, which are oppositely spaced about the envelope axis in alignment with the outer anode extremities, and slightly anodeward from the shield can 9.

The ballasting means 28 and 29, being within the envelope 1 and having a porous surface containing a large quantity of foreign gas, must be heated to high temperature in the de-gassing operation performed on the whole device; this heating must penetrate the whole length of the rods 27r, including the portions in contact with the sleeves and caps. Accordingly after assembly of the device it will be placed on the pump and exhausted to high vacuum; thereupon an appropriate high voltage will be impressed between the lead-in wires 20 and 21 to pass a current through and thoroughly heat all the ballasting means and the heater 8 and thus to de-gas those means and the electrode 5. To facilitate degassing of the latter and more thoroughly to heat and de-gas the cathode element 6, current may be supplied to the cathode element through the medium of lead-in wires 16 and 19 which are available externally of the device. After the degassing, of course, the rare gas filling and the vaporizable metal (i. e. mercury) is inserted in the device.

The structure of the device of Figure 1 having been thus described, attention may be directed to the manner of its operation, in connection with which will be mentioned certain typical parameters; it will be understood, however, that these parameters are set forth in an illustrative and strictly non-limitative sense.

The device may be considered as adapted for normal operation on commercial alternating current supplies of the usual voltage of 110 or 115 volts, being adapted for connection with a standard light socket by means of the base 37. When the supply is connected, it will be obvious that the anodes are immediately established at an alternating potential difference coinciding with that of the supply—say 113 volts R. M. S.—and that current will flow from between the anodes through the series path offered by ballast portions 28a and 28b, the heater halves 81 and 82, and the ballast portions 29b and 29a; this establishes the cathode element 6 and the shield can 9 (which are connected to the heater center-tap 75

8c) at a uniform mid-potential; exemplarily 56.5 volts R. M. S. from each anode. By the current flow through the heater winding 8 the cathode is heated, and after an interval becomes emissive.

5 It will be seen that throughout this heating interval the bottom caps 32 and 33 are at alternating potentials different from that of the cathode element 6 by the alternating voltage drop in half the heater winding, and hence are made 10 alternately positive with respect to the cathode element by the peak value of this voltage drop. This peak voltage drop is made somewhat higher than the ionization potential of the rare gas filling, by suitable apportionment of the resistance values of the ballasting means and heater. Accordingly when the cathode becomes emissive the 15 mentioned potentials on the bottom caps, which are very near the aperture 10 in the top shield end member 13, will introduce ionization of the 20 gaseous filling and a discharge between the bottom caps alternately and the cathode element. It may here be mentioned that while the bottom caps have just been described as effecting this action and are suitably positioned therefor, it 25 may be preferable to connect to each a starting electrode plate which may be disposed a little nearer the axis of the envelope and thus in a still more favorable position with respect to the aperture 10 to effect this action. Such starting 30 electrodes I have illustrated in Figure 1 as 17 and 18, respectively supported on and connected to the bottom caps 32 and 33 by the wires 17' and 18'. Current flow attendant on the discharge just mentioned will of course be limited by both 35 the ballasting means; but the ions created by the discharge diffuse to the nearby walls of the envelope 1, strongly reducing the negative electronic charges on the envelope walls in the lower envelope portion.

40 Attention is now directed to the sleeves 30 and 31, which are at alternating potentials different from that of the cathode element 6 by the alternating drop in half the heater winding plus the alternating drop in one of the mutually similar 45 lower ballast portions 28b, 29b, and hence are alternating positive with respect to the cathode element by a peak voltage considerably exceeding that of the bottoms caps relative to the cathode element. The above-mentioned clearing of electronic wall charges in the lower envelope portion 50 renders the fields of the sleeves, when positive with respect to the cathode, more effective in the cathode vicinity; and electrons from the initially short discharge path become accelerated towards 55 the sleeves 30—31, this ionizing a longer column and causing a discharge between the sleeves alternatingly and the cathode, and this in turn clearing a further portion of the envelope walls of negative charges. Finally the field of the main 60 anodes 25, 26, becomes effective to extend the discharge throughout the length of the device. Thus by a series of anodic elements at progressive distances from the cathode element and at progressively increasing potential differences there- 65 from I am able to initiate the main arc discharge without resorting to high voltage inductive kicks or high frequency ionizations to overcome the fields of the electronic wall charges.

The anodes 25 and 26 are of course alternately 70 positive. Considering one half-cycle during the main discharge beginning at an instant when both anodes coincide in potential with that of the cathode element (which may be taken as a reference potential), the instantaneous anode 25 potential will begin to rise and the instantaneous

anode 26 potential correspondingly to fall. When the anode 25 has reached an instantaneous positive potential corresponding to the bi-cyclic starting voltage drop in the discharge column (which will be at least slightly greater than the potential gradient as measured over the predominate portion of the half-cycle), the discharge from it to the cathode element comes into play and prevents its further potential rise relative to the cathode element. The cathode element potential thereupon diverges positively from the mid-potential of the supply—or, relative to the cathode potential, the anode 26 potential continues its negative increase at a higher rate to the peak of the half-cycle, when it will be of a negative value equal to 15 the peak supply voltage less only the potential gradient of the column. In the declining half of the half-cycle the negative potential of the anode 26 decreases at the higher rate, and the positive potential of anode 25 remains constant at the 20 value of the potential gradient, until late in the half-cycle when the positive and negative anode potentials again become symmetrical about the cathode element potential and together fall from the value of the predominate potential gradient 25 to zero at the normal rate, the discharge extinguishing. In the next half-cycle the action of course is repeated, but with the anodes interchanged; and so on.

When the main discharge is first initiated the 30 potential gradient in the discharge column is relatively low, being determined essentially by the rare gas filling and being typically of the order of 22 to 25 volts. The current and power in the device, being limited by the ballast means 35 connected to the momentarily more negative anode and being quantitatively the quotient of the potential of this anode (relative to the cathode element) by the resistance of this ballast means, is now considerably increased over that 40 obtaining during the heating period. This increase, however, is represented almost exactly by power in the discharge column; the R. M. S. or heating value of the current (and hence the average power) in the two ballast means and 45 heater halves, taken over a whole cycle, has not materially changed—for while the voltage across and current through one ballast means and half-heater have been materially increased in one half-cycle, they have been substantially correspondingly reduced in the next half-cycle by the shunting action of the discharge. The heat inertia of the ballast means is sufficiently high so that, while the ballast temperature and resistance may yet respond quite rapidly to appreciable R. M. S. 55 current changes, they do not significantly change with these intra-cyclic variations.

As the main discharge continues the device and its envelope 1 are being heated up by the ballasting means, heater and discharge column, 60 and the vapor density and pressure are rising. After a short interval the vapor density will have risen to the order of the gas density and the whole discharge current will be carried by the vapor ions, which have a lower ionization potential than 65 the rare gas. As the vapor density yet continues to rise the potential gradient will increase, with increasing temperature of the device, until at some temperature the device will stabilize by radiating the same amount of energy as is being 70 supplied to it. At this point the effective or R. M. S. voltage across the discharge column may have increased for example to the order of 31 to 36 volts (roughly the equivalent of 35 to 40 volts potential gradient as measured over the 75

predominate portion of each half-cycle). Under these conditions the currents through either ballast means and associated half-heater in successive half cycles will obviously vary slightly less 5 between those half-cycles than in the early period of the main arc discharge.

While after the discharge has re-started each half-cycle an essentially constant or predominate potential gradient persists until discharge extinguishment late in that half-cycle, the re-starting 10 gradient or requisite potential for re-starting in each successive half-cycle is somewhat in excess of this predominate gradient value. It is very essential that the cooling facilities of the device be so arranged that the stabilization of temperature and vapor pressure of the device occur at a 15 point where the predominate potential gradient will be only a fraction of half the peak supply voltage, so that an ample margin will be provided for this excess, for line voltage fluctuations, 20 for the reduction of stroboscopic effects, and for stability generally. Of course the vapor pressure is determined by the coldest spot of the wall of envelope 1, which may be the bottom portion of 25 the envelope, and it is largely the cooling facility of this section which determines the vapor pressure. Accordingly I may place about the lower end of the envelope, adjacent this section, a thimble 36; by choice of the material of this 30 material such as Bakelite I may control to some extent the radiation from and cooling facility of this section and hence the vapor pressure and potential gradients. In other words, the same 35 type of device may be used in different supply voltages and adjusted to proper operation by changing this thimble.

Assuming the device to be adjusted for 40 volt predominate potential gradient, and to be provided with ballast means and heater winding such 40 that the normal hot resistance of each ballast and associated half-heater is of the order of 38 ohms, the device on 113 volts supply will draw approximately 2.1 amperes R. M. S., the R. M. S. current 45 through any portion of the ballast-heater system over a whole cycle will be of the order of 1.6 amperes, the average current through the discharge column of the order of .9 ampere, and the power consumptions in the ballast-heater system 50 and in the discharge column may be of the order of 200 and 36 watts respectively. While it is true that the energy in the luminous column represents only a little over 15% of the total energy expended, it is to be borne in mind that this 55 efficiency is a minor factor compared with simplicity, capability of complete self-contained nature, and operation in standard sockets and without the air of experts—particularly for such special purposes as a health lamp. In the example 60 cited, with a discharge column length of the order of 15 to 18 centimeters, the emission from the rather dense vapor through the "Uviolet" or "Corex D" glass contains a very considerable ultra violet radiation—from which by the filter 65 action of the glass is quite sharply excluded the undesirable shorter wavelength radiations below the 2900 Angstrom unit lower limit of the Dorno spectrum.

By the same token that considerable power is 70 expended in the ballasting means, these means are of such relative magnitude as to result in excellent uniformity and stability for the system in the face of supply voltage variations—provided of course that the predominate potential gradient 75 of the discharge column is made a reasonable one

as above discussed. This effect is assured not merely by the magnitude of the ballasting means but also by their high resistance-temperature coefficient, for on supply voltage fluctuations they change their resistance and tend to maintain a constant discharge column current and energy. The uniformity of operation of the device in the face of temperature changes, whether produced internally or externally of the device, is also good—for while the column will change its potential gradient with temperature changes, a 10 gradient increase will reduce the potential across and current through the ballasting means and hence the current in the column (and vice versa), thus the energy in the column stays rather constant, whether it results from a higher gradient 15 and lower current or vice versa.

The arrangement of the ballasting means in shunt to the supply permits the simple arrangement of the heater in series with the ballasting means, for the heater will receive the necessary immediate current upon connection of the supply. Furthermore, in view of the voltage-dividing action of the ballasting means with resulting shunting of alternate portions by the discharge column, the natural increase of current through one portion of the ballasting means by the discharge in any one half-cycle is compensated for by a reduction in current through the other portion, so that the R. M. S. current through any one portion of the ballasting means over a whole cycle is maintained substantially unincreased upon initiation of the discharge; accordingly the heater, in series with the ballasting means 28-29 and thus effectively forming a portion of the total ballasting means, is not overheated during the main discharge. The preferred division of the heater into halves respectively connected in the two portions of the voltage divider system results under all conditions in symmetry of the currents and discharge characteristics in successive half cycles, which might otherwise be upset by different thermal inertiae of the heater and ballasting means and possibly different resistance-temperature coefficients. Furthermore the heater by virtue of this symmetrical division may be availed of as the voltage dividing means for establishing suitable symmetrical initial starting potentials.

The resistance of each ballast means and half-heater—above mentioned as typically about 38 ohms in normal hot condition for a device with the exemplary parameters abovementioned—should be suitably apportioned between the ballast means portions (e. g. 28a, 28b) and the half-heater to provide useful voltages for the initial starting electrodes (e. g., 17, 18) and the intermediate starting electrodes (e. g., 30, 31). Hot resistances very approximately in the ratios of 3:2:3 for the ballast portion 28a (or 29a), ballast portion 28b (or 29b) and half-heater 81 (or 82) 50 respectively may be found useful; it is to be noted, however, that the cold resistances may be in somewhat different ratio (i. e., that of each half-heater relatively less) in view of a somewhat greater temperature attained in operation by the heater than by the ballasting means 28 and 29. The latter temperature is preferably maintained not too great—for example it may be maintained under operating conditions around 1000 degrees centigrade and not above 1400 degrees centigrade. 55 In a device of the approximate operating parameters exemplarily set forth above I have employed, for the material of the resistance element 27 of the ballasting means, tungsten wire as used for commercial 300 watt incandescent 110-120 volt 60 65 70 75 75

lamps—but with the difference that the spirals have been made of greater diameter and larger pitch.

In the structure of Figure 1 the resistance elements 27 of the ballasting means are imbedded in the rods 27^r to shield them effectively from the discharge, for otherwise ionic bombardment of the element would lead to disintegration, and the heated elements would cause cross-arching within the tube; the ballasting means are spaced sufficiently on opposite sides of the envelope axis to avoid serious effect on the potential gradient of the discharge column. In Figures 6 and 7 I illustrate a modified form of the device wherein the most essential change is the protection of the resistance elements 27 of the several ballasting means portions by their enclosure in sealed glass tubes to form lamps (44a, 44b, 45a and 45b) of the order for example of 12 millimeter diameter, which are evacuated and preferably filled with an inert gas of about $\frac{1}{2}$ atmosphere pressure similarly to ordinary gas filled lamps. It is essential that the ballasting means remain sufficiently spaced away from the envelope axis to avoid seriously raising the potential gradient of the discharge column, and in view of their increased diameter it is necessary to widen the envelope 1 throughout most of its length. Accordingly it may conveniently be provided with the central portion 1' (opposite the discharge column) of flattened or approximately elliptical cross-section, the lamps being located roughly in the foci of the approximate ellipse as appears in the sectional Figure 7; this avoids the somewhat undesirable large cross-section of the discharge path were there employed simply a circular envelope cross-section of larger diameter.

In Figure 6 by way of alternative illustration I have shown cylindrical carbon anodes 41 and 42 supported on the lead-in wires 28 and 29 (with wires 53 and 54 also supported on these lead-in wires and extending outwardly to support and connect to the upper ballast means 44a and 45a). These anodes may be shielded from each other, for minimization of disintegration and cross-arching propensities with higher supply voltages, by the conductive or insulating shield 43 interposed therebetween and supported in a wire 43' sealed in the stem 2.

In order to provide intermediately active starting electrodes analogous to the sleeves 30 and 31 of Figure 1. I may again divide each ballasting means into upper and lower portions comprising lamps 44a and 44b respectively, and 45a and 45b, respectively. These portions may be joined by wire 48 on the one hand and wire 49 on the other, and intermediate starting electrode plates 46 and 47 supported and connected to these respective wires by wires 46' and 47'. To retain the junctions of upper and lower lamps against transverse movement wire spiders 50 and 51 may be secured to the wires 48 and 49, and led around and biased against the interior wall of the envelope section 1' into mechanical connection with each other—which connection is however insulated by blocks 52 of insulating material to avoid short-circuiting the wires 48 and 49.

I have found that in devices of medium length (e. g., of about 15 centimeters discharge column) the main discharge can be introduced even though the intermediate starting electrodes (e. g., sleeves 30 and 31 or electrodes 46 and 47) are omitted and each of the two ballasting means made in one integral part. This is particularly the case when, as especially true of the lamps of Figure 6, the

cooling period of the ballasting means is small compared to that of the electrode 5 and heater winding 8 therein. For in this case one can connect the supply for a sufficient interval to heat the cathode element to emissivity and develop a discharge to the initial starting electrodes (e. g., 17, 18), interrupt the supply for a few seconds to permit the ballasting means to cool, and again connect the supply. On this second connection the main discharge will dependably start for the following reason: In the period of supply interruption the ballasting means cools rapidly and lowers its resistance greatly in accordance with its high coefficient, but the heater 8 retains substantially its normal hot resistance; therefore for a brief interval on the reconnection of the supply the voltage drop across the heater will be much higher than normal and much higher potentials relative to the cathode element will appear on the initial starting electrodes. These then increasingly accelerate electrons from the cathode, spreading an impulse of ionization far up along the discharge path toward the main anodes and permitting the main discharge to strike therefrom.

With the omission of the intermediate starting electrodes it becomes possible to arrange the ballasting means outside the envelope 1; a typical such arrangement I have illustrated structurally in Figure 8 and schematically in Figure 9. Before referring more detailedly to these figures, I may mention that in each of the ballasting means in these figures I have shown an inductance. It will be understood that this partial use of inductive ballasting means is optional; its general advantages are the permissible reduction of pure resistance value of the ballasting means resulting in lowered power consumption and increased power efficiency, and slight prolongation of the discharge in each half cycle resulting in increased stability and/or the ability to operate the discharge column at a somewhat higher potential gradient; its disadvantages are obviously somewhat increased cost, and an impairment of power factor to a degree generally corresponding to the degree of power efficiency increase. When inductance is employed, I prefer so to limit its value as to maintain a power factor of the order of 75 or 80%. It will be understood, of course, that the inclusion of the inductive ballast portions does not alter the basic action of the system, nor impair its most fundamental advantages.

In Figure 8 the device 1 may be generally similar to that of Figure 1, excepting that the ballasting means 28a, 28b, 29a, 29b (with the intermediate starting electrode means) are omitted from within the device, and merely by way of illustration, the anode structure of Figure 6 has been employed. The Edison base 37 of the device has been shown screwed into the inverted socket 38; this is secured in the center of a downwardly directed reflector 10. On either side of the socket 38 are also secured to the reflector the inverted sockets 62 and 63; into these sockets are screwed the resistive ballasting means 60 and 61 in the physical form of evacuated or gas-filled light bulbs having as their filaments the necessary ballast resistance wire 27. Over the bottom extremity of the device 1 is secured the Bakelite or other cap 80 carrying terminals 14" and 15" to which the wires 14 and 15 are respectively connected, being thereto extended through the stem 2. Beaded or other wires 14' and 15' are removably connected to these respective terminals, and lead therefrom to the respective ter-

5 minals 62' and 63' of sockets 62 and 63. The other terminals of these sockets are connected by respective conductors 64 and 65 to respective inductance coils 66 and 67, and therethrough (at points 20'' and 21'') to the respective leads 20' and 21' passing upwardly from socket 38.

10 These coils 66 and 67 may be wound about the respective core elements 66' and 67'. While these elements may be entirely distinct, it is convenient to arrange them as opposite legs of a common core 68 which is closed (except for a possible small air-gap); when this common core arrangement is employed it is desirable to arrange the coils electrically in that mutual phase relationship, 15 readily determined by test, which yields the more stable system operation tendencies—resulting from the mutual coupling of the coils through the common core.

15 The core elements or common core may be secured to the top of the reflector 70 as by bracket 69. Above the coils may be provided the inverted pan-shaped member 71 secured around its periphery to the top of reflector 70 and thus enclosing the coils. On the top of this member 25 71 may be secured the Edison base 72 having relatively insulated shell 72a and tip contact 72b to which the leads 20' and 21' are respectively connected. By means of this base 72 the entire assembly may be screwed into any available commercial supply line socket, forming a 30 convenient arrangement in which the device 1 and lamps 60 and 61 are each readily replaceable by the layman at any termination of their useful life.

35 It will of course be understood that the filaments of the bulb lamps 60 and 61 of Figure 8, or the tubular lamps 44a, 44b, 45a, 45b of Figure 6, may be apportioned to operate at temperatures yielding considerable light output, so the total 40 light-producing power efficiency (as distinguished from the discharge column light-producing power efficiency hereinabove considered) may in any event be maintained very good.

45 The general construction illustrated herein for the electrode 5 is similar to an electrode construction shown in a co-pending application just filed by me, excepting that in that application the heater winding was not center-tapped. As 50 pointed out in that application, the spacing between the can 9 and the heater 8 should be made of the order of the mean free path length of electrons in the gaseous filling within the can at operating temperatures, in order to minimize danger of cross-arching between can and heater 55 or between portions of the heater. Also, as pointed out in that and a prior co-pending application in connection with a helical cathode element of the type of 6 herein, the internal diameter of the helix should be made several times 60 the mean free path length of electrons in the gaseous filling within the cathode enclosure at operating temperatures, so that there may develop within and not outside the enclosure an ion cloud or region of intense positive ionization. It 65 will of course be appreciated that in the instant invention other forms of cathode than the helical element 6 may be employed, but preferably when a cathode enclosure is provided the ion cloud will be maintained within the enclosure.

70 It may further be particularly mentioned, in connection with the heater winding 8 which I have illustrated and described, that it is very desirable to form this and the coating 8' on the cylinder 7 in a similar manner to that which I 75 have disclosed for the preparation of resistance

rods 21r. That is to say, the winding 8 is preferably made on a cylinder or tube 7 which is semi-plastic or hardened but not yet sintered, the coating 8' of similar material to the cylinder 7 is sprayed or otherwise coated over the winding, 5 and the wound and coated cylinder is then heated and sintered as a unit; thus the winding 8 becomes imbedded in a homogeneous mass relatively free of strains which might later tend to cause the coating 8' to crack off.

10 It has been most convenient in the description to refer by the term "ballasting means" to the elements shown as connected from the heater extremities to the anodes. It will be appreciated, however, that the heater and its respective halves 15 are likewise portions of the actual ballast; and the term "ballasting means" and the like, being employed in the claims in a broad context, will therein be understood to include within its scope the heater and its halves.

20 I do not intend that the scope of my invention be limited by the details of the particular embodiments and structures shown and described, as it will be obvious that these may be modified without departure from the spirit of the invention. And 25 it is my intention to claim herein, as broadly as the state of the art will permit, all the various novel combinations, sub-combinations and features herein disclosed.

20 I claim:

1. In combination in an electric discharge system: a source of alternating current; ballasting means connected across said source; and a gaseous discharge device including a thermionic cathode electrically connected to a point of intermediate potential in said ballasting means, two anodes electrically connected to points in said ballasting means of respectively opposite potential difference from said cathode, and starting electrode means disposed near said cathode and 35 electrically connected to at least one point of intermediate potential in said ballasting means.

2. In combination in an electric discharge system: a source of alternating current; ballasting means connected across said source; and a 45 gaseous discharge device including a thermionic cathode electrically connected to a point of intermediate potential in said ballasting means, two anodes electrically connected to points in said ballasting means of respectively opposite potential 50 difference from said cathode, and a plurality of starting electrode means in progressive spacing from said cathode toward said anodes and respectively connected to points in said ballasting means of progressive potential differences from said 55 cathode.

3. In combination in an electric discharge system: a gaseous discharge device comprising a gaseous filling, a heater winding, a thermionic cathode adjacent and influenced by said heater 60 winding and connected to a point thereon, and two anodes adapted for connection across an alternating current supply; two ballasting means each connected from a respective one of said anodes to a respective extremity of said winding, 65 of such magnitude as to cause a voltage drop, between said winding point and at least one of said winding extremities, in excess of the ionization potential of said gaseous filling; and starting electrode means adjacent said cathode and 70 electrically connected to at least said one winding extremity.

4. In combination in a gaseous discharge device: an elongated envelope and therewithin a gaseous filling, a cathode near one envelope ex- 75

- 5 tremity, and two anodes near the other envelope extremity and adapted to have impressed therebetween an alternating voltage and to support a discharge alternatingly to said cathode: said anodes being of refractory metal, having flanges mutually parallel and spaced apart a distance of the order of the mean free path length of electrons in said gaseous filling at operating temperatures, and each anode having a discharge-supporting surface bent outwardly from its said flange and facing in a direction outwardly divergent from the direction of said cathode.
- 10 5. In combination in a gaseous discharge device: a cathode, and two anodes relatively spaced from said cathode and adapted to have impressed therebetween an alternating voltage, said anodes being of refractory metal, each having flange and active surfaces at an acute angle relative to each other, and being mutually arranged with their 15 said flange surfaces parallel and closely spaced and with said angles pointing toward said cathode.
- 20 6. In combination in an electric discharge system: a gaseous discharge device comprising a heater winding, a thermionic cathode adjacent and influenced by said winding and connected to a point thereon, and two anodes adapted for connection across an alternating current supply; two ballasting means each connected from 25 a respective one of said anodes to a respective extremity of said winding; and starting electrode means within said device adjacent said cathode and electrically connected with said heater winding.
- 30 35 7. In combination in an electric discharge system: a gaseous discharge device comprising a heater winding, a thermionic cathode adjacent and influenced by said winding and connected to a point thereon, and two anodes adapted for connection across an alternating current supply; two ballasting means each connected from 35 a respective one of said anodes to a respective extremity of said winding; and starting electrode means within said device adjacent said cathode and electrically connected to intermediate points 40 in said ballasting means.
- 45 8. In combination in a gaseous discharge device: an elongated envelope; two anodes adapted for connection to an alternating current supply,
- 5 disposed within said envelope near one extremity thereof; a thermionic cathode disposed within said envelope near the other extremity thereof and adapted to receive a discharge from said anodes; a heater winding disposed in heating relationship to said cathode and intermediately connected thereto; two resistance elements disposed within said device and each electrically connected from a respective extremity of said winding to a respective said anode; and starting electrode means connected with at least one of said resistance elements remotely from either of said anodes.
- 10 9. In a gaseous discharge device having an envelope and means, including main electrodes, for maintaining a discharge therewithin; two serially arranged resistances disposed within said envelope; insulating tubings enclosing said resistances; and a metallic sleeve fitting about an end of each of said tubings, electrically connected with an end of each of said resistances, and exposed to the space within said device for action as an auxiliary electrode.
- 15 10. In combination in a gaseous discharge device: an elongated envelope, discharge-supporting electrodes near respectively opposite extremities of said envelope, and two resistances extending longitudinally of said envelope therewithin, said envelope having a cross-section substantially in the form of an ellipse, and said resistances being disposed approximately at the 20 foci of said ellipse.
- 25 11. In combination in a gaseous discharge device: an elongated envelope, discharge-supporting electrodes near respectively opposite extremities of said envelope, and a resistance extending longitudinally of said envelope therewithin, said envelope having a cross-section substantially in the form of an ellipse, and said resistance being disposed approximately at a focus 30 of said ellipse.
- 30 12. In a gaseous discharge device having an envelope and means for supporting a discharge therewithin: ballasting means within said envelope for said discharge, and auxiliary starting 35 electrode means permanently connected to an intermediate point in said ballasting means.
- 40

CARL J. R. H. von WEDEL.

Patent No. 2,172,631.

CERTIFICATE OF CORRECTION.

September 12, 1939.

CARL J. R. H. von WEDEL.

It is hereby certified that error appears in the printed specification of the above numbered patent requiring correction as follows: Page 1, first column, line 13, for the word "objects" read object; and second column, line 54, for "anode" read anodes; page 3, second column, line 52, for "i.e." read e.g.; page 4, second column, line 2, for "instantaneous" read instantaneous; page 5, first column, line 58, for "air" read aid; and second column, line 37, for "dischage" read discharge; page 8, second column, line 16, claim 9, after "therewithin" change the semicolon to a colon; and that the said Letters Patent should be read with this correction therein that the same may conform to the record of the case in the Patent Office.

Signed and sealed this 14th day of November, A. D. 1939.

(Seal)

Henry Van Arsdale,
Acting Commissioner of Patents.
